UNITED STATES PATENT OFFICE.

JOHN J. FLYNN, OF PROVIDENCE, RHODE ISLAND.

THREADING-TOOL.

1,259,504.

Specification of Letters Patent. Patented Mar. 19, 1918.

Application filed July 30, 1917. Serial No. 183,411.

To all whom it may concern:

Be it known that I, JOHN J. FLYNN, a citizen of the United States, residing at Providence, in the county of Providence and State of Rhode Island, have invented certain new and useful Improvements in Threading-Tools, of which the following is a specification.

My invention relates to threading tools and especially to die holders of the opening type adapted for use in turrets and other supports of screw machines.

The essential objects of my invention are to render the chasers and constituent parts of the device accessible; to insure the chasers against play whereby they would "bell mouth"; to securely hold the same under compression; to afford auxiliary adjustment for the chasers; to facilitate assemblage and disassemblage of the parts; to insure a maximum rigidity of all the parts during operation, as well as to maintain perfect alinement thereof; and to provide in a single structure means for finishing as well as for roughing 25 the work.

To the above ends essentially my invention consists in such parts and combinations of parts as fall within the scope of the appended claims.

30 In the accompanying drawings which form a part of this specification,

Figures 1 and 2 are end and side elevations respectively of a threading tool embodying my invention.

35 Figs. 3 and 4, sections of the same on lines 3—3 and 4—4 of Fig. 1,

Figs. 5, 6 and 7, sections on lines 5—5, 6—6, and 7—7 respectively of Fig. 3,

40 Figs. 8, 9, and 10, details of one of the chasers,

Figs. 11, and 12, end and side elevations respectively of the casing or housing,

Figs. 13 and 14 are end and plan elevation respectively of the cam actuating member,

45 Figs. 15 and 16, end and side elevations respectively of the chaser carrier; and

Figs. 17 and 18, similar elevations respectively of the spring retainer.

Like reference characters indicate like parts throughout the views.

The tool comprises a cylindrical housing or casing, comprising a body portion or shell 20, and a hollow stem 22 intended for insertion into a turret, and constitute the supporting member for the parts. The shell 20 has an oblong slot 25 in its side provided with an inclined cam surface 26 at its end.

Slidable in the bore 27 of the stem is the hollow shank 28 of a hollow head 29 shown in detail in Figs. 15 and 16. The inner end 60 portion 30 of the head is of less diameter than the intermediate portion 31, and the latter is of less diameter than the outer portion 32. The extreme outer end of the head is of maximum diameter forming a flange 33 65 adjacent which is a shoulder 34. One or more diametrically disposed undercut or dovetailed guideways 35 are formed in the outer face of the head, and extend into the portion 32 of the latter. Cylindrical cavities 37 in alinement with each other in opposite sides of the portion 32 of the head open into the bottoms of the guideways and form longitudinal slots 38 therein.

Slidable in the guideway are the chasers 75 40 shown in detail in Figs. 8 to 10 inclusive. Each chaser comprises a body having flaring sides 42, and upon one end spaced fingers 43 carrying the cutter teeth 44. Upon its outer end each chaser has three curved shoulders. 80 The upper shoulder or flange 46 extends beyond the intermediate shoulder or surface 47, while the lowest shoulder 48 is eccentric to the other shoulders and constitutes a cam surface. In the rear of each chaser near its 85 outer end is fixed a pin 49. These pins extend downwardly into the cavities 37 through the slots 38 into the path of the caps 50, slidably in the cavities upon the outer ends of helical springs 51 seated in the cavities. The springs press outwardly and tend to distend the chasers.

A split ring 53 has a conical exterior slide face 54, and its base abuts against the end face of the portion 23 of the casing. The 95 space 55 between the ends of the split ring

is ample to loosely receive a pin 56 in casing, and to allow a contraction of the ring. This contraction is effected by a collar 58 provided with a conical opening 59 adapted 5 to embrace the surface 54 of the split ring. In the rear end of the collar is an internal thread 60 engaging the thread 24. A set screw 62 seated in a threaded opening 63 in the collar and adapted to engage the 10 thread 24 serves to hold the collar in any axial position of adjustment.

Since the split ring embraces the flanges 46 of the chasers it is evident that as the collar in its rotation moves rearwardly the 15 ring 53 contracts and causes the cutting ends of the chasers to approach each other.

The primary means for closing the chasers consists of a sleeve 65 rotatably mounted upon the portions 31 and 32 of the head 20 20 29 within the casing 20, and shown in detail in Figs. 13 and 14. The end of this member abuts against the rear face of the step 34 of the head, and at diametrically opposite points the upper portion is provided with marginal open slots 67, and centrally of each slot is a deeper slot 68. The 25 resultant spaced shoulders 69 formed by the slots 67 have cam faces 70 and the portions of the sleeve adjacent the slots 68 are internally cut away to form inclined surfaces 72. The described sleeve is manually turned a portion of a rotation by means of a handle 74 fast in the sleeve extending through the slot 26. Since the cam faces 48 on the chasers are in the path of the shoulders 69 as the sleeve is turned, one of each pair of cam faces 70 moves over the faces 48 and compresses the chasers so that the flanges 46 of the latter may enter the split ring 53.

40 Integral with or fixed to the head 29 by a screw 74 or otherwise is a collar 76 on which slides the rear face of the sleeve 65, and which is provided adjacent the latter with an annular channel 77. A pin 78 in collar extends into this channel. A pin 79 on the sleeve 65 also extends into this channel at a point opposite the first pin. A helical compression spring 80 is located in channel and bears against both pins at its ends. 45 In this instance bearing blocks 81 upon the ends of the spring contact with the pins. This spring tends to rotate the sleeve 65 only, since the head 29, although longitudinally slidable, is held against rotation by external lugs 83 on the collar 76 slidable in longitudinal grooves 84 in the casing 20. The action of the spring is upon the member 65 in a direction opposite to direction of manual movement of the handle 74.

50 For the purpose of moving the head 29 longitudinally the stem 22 has an enlarged bore 86 in its rear end in which is mounted a compression spring 87 engaging one end

88 of the bore, and a collar or nut 89 slidable in the stem and having an internal 65 thread 90 engaging an external thread 91 on the shank 28.

This collar is in the present instance threaded to make it possible, by screwing the same, to vary the tension on the spring 70 87. The latter acts to retract the head 29 rearwardly into the shell after the cam sleeve 65 has retracted the chasers. Vent holes 93 in the rear wall of the shell are convenient to prevent an air cushion when 75 the head is retracted.

The operation of the parts thus far described is as follows: The stem 22 being fast in the turret, the latter moves horizontally advancing the shell 22 together with the 80 head 29 in the direction of the arrow shown in Fig. 4, the desired distance of cutting. During this advance the work, while rectilinearly stationary, is being rotated whereby the teeth of the chasers are enabled to cut 85 the blank. At the moment the casing discontinues its advance the continued rotation of the work co-operates with the teeth of the chasers to draw the head farther in the direction of the arrow against the tension of 90 the spring 87 whereby the flanges 46, of the chasers advance beyond the split ring 53 and thereupon are expanded by the tension of springs 51, and the work is released.

The initial step in closing the chasers is 95 effected as already described by partially rotating the chaser closer or cam sleeve 65 by its handle until the flanges of the chasers are contracted sufficiently to enter the bore of the split ring. The handle is then rearwardly induced by the cam 26 and the spring 87 whereby the head is pushed and drawn to bring the outer faces of the chasers back to original position. Micrometric adjustment of the chasers is next attained 100 by turning the collar 58.

In the present instance a slight space 95 occurs between the end wall 96 of the shell 22 and the rear end of the head 29 to permit a rearward telescoping or yielding of the 110 head. In this connection the latter has cavities 97 in each of which is a spring 98 pressing upon the end of a slidable pin 99 which projects beyond the face of the head and contacts with the inner face of the casing 115 wall 97. In the usual or roughing operation of the threading tool the pins 99 may be removed as they are unnecessary. If, however, it is desired to finish a thread by recutting, the insertion of the already 120 threaded blank into the head so as to insure true registration of the old thread with the chaser teeth is facilitated by the yielding capacity of the head.

I claim:

1. In a threading tool, the combination

with the head and casing, of chasers yieldingly mounted in the head, a collar adjustably mounted on the casing and provided with a cam opening, and a split ring registering in said opening and embracing the head and chasers.

2. In a threading tool, the combination with the head, of chasers yieldingly mounted in the head, a casing exterior of the head provided with a thread, a yielding ring abutting against the casing and embracing the chasers, and a collar slidably embracing the ring and provided with a thread loosely engaging the first thread.

15 3. In a threading tool, the combination with the head provided with radial cavities, chasers slidably mounted in the head in alinement with the cavities, pins on the chasers extending into the cavities, springs 20 in the cavities engaging the pins, a casing surrounding the heads, a yielding member embracing the chasers, and a cam collar embracing the yielding member adjustably mounted on the casing.

25 4. In a threading tool, the combination with the casing provided with an oblong opening, of a head mounted in the casing, a rotary sleeve upon the head provided with open marginal slots, cam shoulders on the sleeve at the sides of the slots, a handle in the sleeve extending through the opening, chasers yieldingly mounted in the head in alinement with the slots, cam faces on outer ends of the chasers adapted to engage the 35 cam shoulders, a split ring embracing the chasers and provided with an inclined outer face, and a collar embracing the ring and adjustably mounted on the casing.

5. In a threading tool, the combination 40 with the casing provided with an oblong opening, of a head mounted in the casing, a rotary sleeve upon the head, cam shoulders on the sleeve, a handle in the sleeve extending through the opening, a spring in the head impelling the sleeve and head in opposite directions, chasers yieldingly mounted in the head, cam faces on the chasers in the path of the cam shoulders, and a collar on the casing surrounding the head.

50 6. In a threading tool, the combination of a casing provided with an opening and with longitudinal grooves, a longitudinally 55 slideable head mounted in the casing, lugs upon the head registering in the grooves, a rotary cam sleeve upon the head, resilient means for actuating the sleeve, a handle on the sleeve extending through the opening, a collar on the sleeve surrounding the head, chasers yieldingly mounted on the head, and 60 springs in the head engaging the chasers.

7. In a threading tool, the combination of a casing provided with an opening, a longitudinally slideable head mounted in the

casing, chasers yieldingly mounted in the head, a resilient member embracing the 65 chasers, springs in the head pressing the chasers against said member, a collar adjustably mounted on the casing embracing said member, a rotary cam sleeve upon the head adapted to engage the cams in its rotation, an arcuate spring engaging the cam sleeve and head, and a handle on the sleeve extending through the opening.

8. In a threading tool, the combination of a casing provided with an opening, a stem 75 upon the casing, a longitudinally slideable head mounted in the casing, a shank upon the head slideable in the stem, a spring upon the shank engaging the stem, chasers yieldingly mounted in the head, means upon the 80 casing for retaining the chasers, an oscillatory cam sleeve upon the head movable into the paths of the chasers, and a handle on the sleeve extending through the opening.

9. In a threading tool, the combination 85 of a casing provided with an opening, a stem upon the casing, a longitudinally slideable head mounted in the casing, a shank upon the head slideable in the stem, an adjusting nut on the end of the shank within the stem, 90 a spring upon the shank having one end abutting against the nut and the other end engaging the stem, chasers yieldingly mounted on the head, means upon the casing for retaining the chasers, a reciprocating 95 cam sleeve upon the head adapted to engage the chasers, and a handle on the sleeve extending through the opening.

10. In a threading tool, the combination 100 of a casing provided with an opening, a stem on the casing, a longitudinally slideable head mounted in the casing, a shank upon the head slideable in the stem, a spring upon the shank engaging the stem, chasers yieldingly mounted in the front end of the head, 105 means upon the casing for retaining the chasers, an oscillatory cam sleeve upon the head movable into engagement with the chasers, a handle on the sleeve extending through the opening, and yielding members 110 engaging the rear end of the head and the casing.

11. In a threading tool, the combination 115 of a casing provided with an oblong opening, and with a cam face at one end of the opening, a longitudinally slideable head mounted in the casing, chasers yieldingly mounted in the head, a cam sleeve loose on the head adapted to engage the chaser, and a handle fast to the sleeve extending through 120 the opening adapted to engage the cam face.

12. In a threading tool, the combination 125 of a casing provided with an oblong opening, and with a cam face at one end of the opening, a longitudinally slideable head mounted in the casing, chasers yieldingly

mounted in the head, an oscillatory cam sleeve loose on the head adapted to engage the chasers, a handle, fast to the sleeve extending through the opening, and spring means within the casing for oscillating the handle in one direction.

13. In a threading tool, the combination of a casing provided with an oblong opening, and with an inclined cam face at one 10 end of the opening, a stem on the casing, a longitudinally slideable head in the casing,

a shank on the head slideable in the stem, a spring upon the shank engaging the stem, chasers yieldingly mounted in the head, an oscillatory cam sleeve upon the head movable into engagement with the chasers, and a handle on the sleeve extending through the opening. 15

In testimony whereof I have affixed my signature.

JOHN J. FLYNN.
